UNITED STATES PATENT OFFICE.

JOHN J. KNAPPENBERGER, OF GREENSBURG, PENNSYLVANIA.

HOT-AIR FURNACE.

SPECIFICATION forming part of Letters Patent No. 651,763, dated June 12, 1900.

Application filed August 26, 1899. Serial No. 728,533. (No model.)

To all whom it may concern:

Be it known that I, JOHN J. KNAPPENBERGER, a citizen of the United States, residing at Greensburg, in the county of Westmoreland and State of Pennsylvania, have invented 5 certain new and useful Improvements in Hot-Air Furnaces, of which the following is a specification.

My invention relates to hot-air furnaces, 10 the primary object being to avoid waste of heat and to utilize the heat arising from the products of combustion which ordinarily escapes through the smoke-flues of a furnace.

Further objects of the invention are to effectually prevent the escape of gases from 15 the combustion-chamber of the furnace into the hot-air chamber thereof and to provide an improved construction which will insure a regular flow of heat to the hot-air flues.

20 The construction of the improvement and its novel features will be fully described hereinafter and defined in the appended claims in connection with the accompanying drawings, which form a part of this specification, 25 and in which—

Figure 1 is a front elevation of a furnace embodying my invention. Fig. 2 is a central vertical section thereof. Fig. 3 is a horizontal sectional view on a plane extending through 30 the fuel-opening of the furnace, with the box or casing fitting said opening removed. Fig. 4 is a detail perspective view illustrating the manner of securing the door of the fuel-opening in position. Fig. 5 is a detail sectional 35 view showing the means for connecting the dome of the combustion-chamber to the inner wall thereof.

The reference-numeral 1 designates the outer wall or casing of the furnace, which is 40 preferably circular in cross-section and built of fire-brick and of rounded or dome shape at its upper end. Within the outer wall 1 is an inner casing 2 of fire-brick, constituting the combustion-chamber and built concentric 45 with the outer wall 1 and at a sufficient distance therefrom to leave an annular hot-air space 3 between them. The upper end of the inner wall 2 converges to cause the heat to strike its inner surface, and said upper end 50 terminates below the dome or roof of the outer wall and is closed by a cast-metal dome 4, formed with an annular horizontal flange 5,

which rests upon the top of the wall 2. Surrounding the combustion-chamber 2 is a jacket 6 of sheet metal, which extends above 55 the top of the chamber 2, the annular space between the jacket and outer surface of the dome 4 being filled with fire-clay mortar, as shown at 7, which secures the dome in place and effectually prevents the escape of gases 60 from the combustion-chamber into the hot-air chamber 3. The walls 1 and 2 and jacket 6 rest upon a suitable foundation, and the lower end of the jacket 6 is embedded in a 65 layer 9 of cement.

The walls and jacket are formed with alined openings to receive a metallic box or casing 10, through which fuel is introduced into the combustion-chamber. To secure this casing, the jacket 6 is formed with flanges 11, 70 struck up from the jacket and bolted to the casing, as clearly shown in Fig. 4. The inner end of the casing 10 extends beyond the jacket 6 to form a flange 12 to receive the inner wall 2. A door 13, having the usual damper 14, is hinged to the front end of the casing. Below the casing 10 the jacket 6 and inner wall 2 are formed with an opening 15, serving as a stoke-hole. 75

16 designates the grate, and 17 the ash-pit, 80 of the furnace, a hinged door 18 being employed to close the stoke-hole and ash-pit.

19 designates the smoke-pipe of the furnace, extending from the side of the dome 4 through the outer wall 1, as shown. 85

Any desired number of hot-air pipes 20 extend through the outer wall 1 to conduct the hot air to the various floors or apartments of the building.

A pipe 30 delivers cold air to the chamber 90 3, and it will be apparent that the circulation of the air around and above the combustion-chamber serves to thoroughly heat it without any admixture therewith of gases or products of combustion. 95

The portion of the lining 2 which is below the grate 16 may be of either common brick or fire-brick, while the portion of the lining or inner wall 2 which is above the grate is built of fire-brick laid in fire-clay mortar. 100

I claim—

1. In a hot-air furnace, the combination with an outer wall, of an inner wall constituting a combustion-chamber, and so arranged

within the outer wall as to form an annular hot-air space; a metallic dome having a flange seated on the inner wall; a metallic jacket surrounding the inner wall and projecting 5 above the latter to form an annular space between the jacket and dome; and a filling of plastic material for said space.

2. In a hot-air furnace, the combination with the outer wall of masonry-work closed 10 and rounded at its upper end; of an inner wall constituting a combustion-chamber and arranged within the outer wall concentric therewith to form an annular hot-air chamber; a flanged metallic dome closing the up-

per end of the combustion-chamber; a metallic 15 jacket inclosing the combustion-chamber and projecting above the same to form an annular space; a filling of plastic material within said space; a casing secured to said jacket and extending through the outer wall and the combustion-chamber, and a door for said casing.

In testimony whereof I affix my signature in presence of two witnesses.

JOHN J. KNAPPENBERGER.
